UNITED STATES PATENT OFFICE.

ALBERT H. TAYLOR, OF WASHINGTON, DISTRICT OF COLUMBIA, ASSIGNOR TO WIRED RADIO, INC., OF NEW YORK, N. Y., A CORPORATION OF DELAWARE.

THERMIONIC-VACUUM-TUBE CIRCUITS.

Application filed May 29, 1923. Serial No. 642,277.

My invention relates to a system for voltage regulation in radio or similar apparatus employing vacuum tubes supplied with alternating current for both filament and plate, and the method of accomplishing the same.

An object of the invention is to provide a system wherein the filament voltage and plate voltage will remain substantially constant during the transmission of signals or other use of the apparatus when the load on the system is rapidly changed.

In the operation of a vacuum tube radio set it is essential that the voltage of the filament and plate remain as near constant as possible when signals are being transmitted. Voltage variation, besides creating possible destructive conditions within the set, causes variations of wave length which are extremely objectionable. This variation is particularly bad where both the filament and plate circuits are supplied from an alternating current generator, especially if the frequency of that generator is high, say 25 from 300 to 1000 cycles, because such machines are frequently of the inductor type having a rather large synchronous impedance. The difficulty is still further exaggerated in the case of aircraft sets where the generator must be of a minimum weight for a given out-put, which construction leads to abnormally high internal impedance.

This invention provides a way of employing generators of very considerable internal impedance without any sensible fluctuations in voltage when signals are being transmitted.

In any radio set operated by vacuum tubes supplied with alternating current at high tension on the plates, one or more condensers should be across the terminals of the high tension winding of the transformer in the supply circuit. These condensers are known as radio frequency by-pass condensers and the plate circuit, and allow the passage of high frequency currents around the high impedance transformer windings.

This invention provides for increasing these capacities somewhat beyond the values necessary to by-pass the radio frequency currents of the plate circuit, and thereby causing them to perform a second function. The condensers are adjusted to a value sufficiently high to produce a what leading current from the generator.

The effect of this current is to cause a rise in the generator voltage. To overexcite the field of a synchronous motor is to cause that synchronous motor to take a leading current. Conversely, a generator which is forced by circuit conditions to deliver a leading current will have its fields and therefore its voltage raised. At the same time, the presence of capacity may be thought of as neutralizing the effect of the internal impedance. Since the vacuum tubes themselves constitute a load on the generator, both as to the filaments and the plates, there is sufficient effective resistance in the circuit to prevent any dangerously large current flowing, should the circuit be operated at or near resonance. It is best to operate the circuit a little beyond resonance to get sufficient rise of voltage from the effect of the leading current on the field to overcome voltage losses due to either resistance or inductance in the generator and in the transformers associated with the generator for supplying filament and plate circuits.

Inasmuch as the load on any particular vacuum tube set will depend upon the type of antenna to which it is connected and upon the resistance of that antenna, and inasmuch as the amount of leading current required increases, more or less, in proportion to the output load in order to hold the voltages constant during operation of the set, there may be provided in addition to the

suitable adjustment of the capacities already mentioned, a further adjustment consisting of an additional primary winding on the filament lighting transformer, known as the compensating winding, which winding is in series on the low tension side of the plate load, that is, in series with the primary of the step-up transformer supplying the plates.

This compensating winding may be used to create additional flux in the core of the filament lighting transformer and by suitably connecting the compensating winding may be made to either oppose or aid the flux normally carried by the filament transformer.

This additional flux is, in general, not in phase with the principal flux of this transformer which fact does not in any way interfere with the action of the compensating winding. The necessity for the function of a compensating winding may be best illustrated by an example. Suppose the set has been

operating on a wave length of 507 meters for which the antenna has a certain resistance. The operator then changes wave length to 600 meters where the antenna has 5 a different resistance. It may not be convenient to change the capacities which produce the leading current and normally, if the capacities are just right for 507 meters, they will not be quite right for 600 meters 10 on account of the different load on the plate circuit. The voltage will in this case probably drop a little when the plate circuit is keyed, but this may be readily offset by adding a few turns to the compensating winding. It will be understood that this winding is provided with taps which make the number of turns adjustable. Or, if the set has been adjusted by suitably adjusting the condensers that produce the leading current for 20 600 meters without any turns in the compensating winding and then the set is changed to 507 meters, where, in general, the resistance of the antenna will be higher and the plate load less, the voltage across the filaments may rise when the set is keyed. This 25 may be overcome by suitably connecting in a few turns of the compensating winding by means of adjusting switches in such a way as to oppose the main flux in the filament lighting transformers.

With these and other objects in view, the invention consists in the construction, combination, and arrangement of parts as will be hereinafter described.

35 In order to more clearly illustrate my invention, I shall now describe the preferred embodiment thereof in connection with the accompanying drawing, in which the figure represents a schematic diagram of a circuit 40 arrangement fulfilling the above objects.

Two transmitting vacuum tubes 1 and 2 are connected so that one tube operates on one half of the alternations of the current and the other tube on the opposite half, so 45 that both lobes of the current are rectified and deliver high frequency energy into the antenna. It is to be understood, however, that the invention is not restricted to a set operating on both lobes of the current, but 50 works equally as well on one lobe. The plates of these tubes are supplied with current from the secondary of a step-up transformer 3, a radio frequency choke 4 being placed in series with each plate and a radio 55 frequency choke 5 in series with the grids and grid leak resistance 6. The plate coil is shown at 7, the antenna coil at 8 and the back coupling condenser at 9. The mid point, or neutral, of the high tension transformer 60 secondary 3 is connected to the mid point, or neutral, of the step-down transformer 10 which lights the filaments and which has 65 two radio frequency by-pass condensers 11 and 12 across it. The compensating winding 13 on the transformer 10 is adjustable in the

number of turns, and the sense of the direction of circulation of currents therethrough, and is in series with the primary of 3. The generator is shown at 14. The two condensers 15 and 16 placed across the two plates and acting as radio frequency bypasses for the plate coil have suitable adjustment to a value larger than ordinarily employed for by-pass purposes in radio sets, which provision permits a sufficient lead of 70 the current to obtain good voltage regulation. It will be understood that if it is desired to make these condensers adjustable the compensating winding can be dispensed with. It will also be understood that a very 75 considerable variation of voltage may be corrected without abnormally large capacities at 15 and 16 by use of the compensating winding above, but in this case it will have a larger number of turns than it would have 80 if the capacities are properly chosen. The combination of the two gives an ideal regulation. For instance, satisfactory regulation is obtained on a certain set with a capacity of .002 microfarads at 15 and 16, using a 85 fairly large number of turns in the compensating winding, but by raising that capacity to .014 microfarads, it is found possible to get normal operation on a given wave length without any turns in the compensating winding, and by the addition of a few turns, 90 either adding or opposing as the case may be, the entire range of wave length of the set can be covered with good regulation. Frequently it is not desirable to increase the capacities 15 and 16 because they take considerable current which has to flow to them through the radio frequency chokes. In such an event, a suitable capacity may be put in 95 at 17, shown in dotted lines, across the primary of transformer 3 and whose value is 100 approximately equal N^2C_2 where N is the turn ratio of the transformer. A capacity placed across this primary will have the same effect; it will have to be a much larger 105 capacity but on the other hand, the insulation resistance will be much less and, therefore, the total volume of the capacity, that is, the total volume of dielectric used, will 110 be approximately the same in both cases. 115 The key 18 provides a means for making signals.

It is understood that the above description and accompanying drawing discloses only the preferred form of my invention 120 and that various minor changes in details of construction, proportion, and arrangement of parts may be resorted to within the scope of the appended claims and without sacrificing any of the advantages of my invention.

Having fully described my invention, what I desire to secure by Letters Patent is:—

1. A signal transmission system compris-

ing in combination an electron tube oscillation generator system including a pair of electron tubes each having grid, filament and plate electrodes, input and output circuits interconnecting said electrodes, a source of alternating current for supplying power to the circuits of said electron tubes, and a condenser located in the output circuits of each of said electron tubes, each condenser being of such value as to produce voltage regulation of the source of energy.

2. A signal transmission system comprising in combination a pair of electron tubes, each having grid, filament and plate electrodes, input and output circuits interconnecting said electrodes, a source of alternating current for supplying power to the circuits of said electron tubes, a condenser located in each of said output circuits having such value that voltage regulation of the source of energy is produced, and means for compensating for variations in the supply of energy from said source to the circuits of said electron tubes.

26 3. A signal transmission system comprising in combination a plurality of electron tubes, each having grid, filament and plate electrodes, input and output circuits interconnecting said electrodes, a source of alternating current, independent transformer systems each having primary and secondary circuits, one of said transformer systems being arranged to supply power to said filament electrodes and the other of said transformer systems being arranged to supply power to said plate electrodes, the primary windings of each of said transformer systems being arranged in series with each other and in parallel with said source, a compensating winding in the transformer system which supplies power to said filament electrodes, and a connection between said com-

pensating winding and the primary circuit of said other transformer system whereby variations in load may be compensated by 45 corresponding regulation of the voltage of said source.

4. A signal transmission system comprising in combination a pair of electron tubes connected in balanced relationship, input 50 and output circuits connected with said electron tubes, a source of alternating current for supplying power to the circuits of said electron tubes, means interposed between said source and the circuits of said electron tubes for compensating for variations in the load, and means connected in the output circuits of each of said tubes for regulating the voltage of said source for maintaining the 55 operation of said circuits constant. 60

5. A radio transmission system comprising in combination with an antenna ground circuit, a plurality of electron tubes each having grid, filament and plate electrodes, input and output circuits interconnecting said electrodes, a source of alternating current, a pair of transformer systems each having primary and secondary circuits, one of said transformer systems being arranged for supplying power to said filament electrodes, and the other of said transformer systems being arranged for supplying power to said plate electrodes, the primary windings of said transformer systems being connected in series, and a shunt connection between opposite terminals of said primary windings, said shunt connection including a compensating winding on one of said transformers in series therewith, and means connected in said output circuits for controlling 70 the voltage of the source of power under 75 variable load conditions. 80
